PAPER CUTTING MACHINE

Application filed September 27, 1929. Serial No. 395,515.

The present invention, relating, as indicated, to paper cutting machines, has more particular reference to machines of the type employing a binder for forcibly clamping a 5 stack of sheets of paper against an immovable bed, and a reciprocable knife for severing such sheets along a line proximate to the engaging edge of said binder.

Heretofore, paper cutting machines of the 10 type referred to have usually been provided with wholly mechanical means for operating the binder. Such means, while satisfactory and extensively used, are objectionable because of their complexity, and, moreover are 15 not commonly arranged in such a manner as to permit of independent power movement of the binder. As ordinarily constructed the binder can be independently operated by a 20 manually pressed treadle, but the clamping force exerted is limited by the operator's strength. If power is to be applied to the binder in order to augment its pressure against the paper, it becomes necessary to 25 reciprocate the knife since the binder and knife are so connected to the source of power as to be unadapted to independent power operation. For some purposes, it is desirable not only to forcibly operate the binder 30 independently of any knife movements, but to exert a powerful clamping force over a considerable period of time.

Our invention, with the object of simplifying and improving the construction of paper cutting machines, provides fluid pressure 35 means for operating the binder, such means being adapted to permit of normal operation, and yet designed in such a manner as to make it possible to operate the binder either independently of the knife, or in synchronized 40 relation to the movements of the knife. For effecting this system of binder control, our invention contemplates providing, in combination with a pump and pressure cylinder, a 45 valve for determining the effect of fluid displaced by such pump, this valve being con-

nected to operating gear of such design as to make it possible not only to independently operate the binder either manually or by applied power, but to also maintain it in force-exerting position for any desired period of 50 time.

To the accomplishment of the foregoing and related ends, said invention, then, consists of the means hereinafter fully described and particularly pointed out in the claims. 55

The annexed drawings and the following description set forth in detail certain structure embodying the invention, such disclosed means constituting, however, but one of various mechanical forms in which the principle 60 of the invention may be used.

In said annexed drawings:

Fig. 1 is a side elevational view of a paper cutting machine embodying the present improvements, certain of the parts being broken away and others either omitted or shown diagrammatically to avoid confusion; Fig. 2 is a more or less diagrammatic rear elevation showing some of the parts illustrated in Fig. 1; and Fig. 3 is a diagrammatic view illustrating the interior construction and manner of operation of the pressure cylinder control valve. 70

In the drawings, and with particular reference to Figs. 1 and 2, our invention is shown in association with a paper cutting machine comprising side frames 1 and a bed or table 2. Above the table 2, the side frames 1 are provided with slots 3 for receiving a knife bar 4 which is connected by rods 5 with cranks 6 mounted upon the opposite ends of a horizontal shaft 7. The shaft 7 is driven by another shaft 8 through suitable gears 9 and 10, while the latter shaft is driven through a clutch 11 by a pulley 12 mounted upon a continuously rotating shaft 13 revolved by a suitable motor 14. The shaft 13 carries a second pulley 15 for operating a pump 16, and the shaft 8 carries a brake wheel 17 controlled by a brake band 18. 90

The clutch 11, or more exactly speaking, its operating cone 19, and the brake band 18 are actuated by a rocker shaft 20 which carries a fork 21 and a cam 22, the former, when 5 the shaft 20 is oscillated in one direction, effecting an engagement of the clutch 11, and the latter at the same time releasing the brake band 18 through a pivoted and connected member 23. Similarly, when the shaft 20 is 10 oscillated in a contrary direction, the clutch 11 is disengaged and the brake band 18 tightened around the brake drum 17. For effecting these rocking movements of the shaft 20, a lever 24 is provided, this lever being pivoted upon a transverse rod 25 and provided with extensions 26 and 27. The extension 26 carries a roller for cooperating with a helical or spiral cam 28, and the extension 27, through a rod 29 and a lever or arm 30, rocks 15 the shaft 20 and, therefore, controls the clutch 11 and the brake band 18. When the knife bar 4 has completed a cutting stroke and returned to its upper and inoperative position, the cam 28 lifts the extension 26, thereby disengaging the clutch 11 and applying the 20 brake band 18 to the brake drum 17. For each succeeding stroke of the cutting knife, it is necessary to first rotate the lever 24 about its longitudinal axis, thus freeing the 25 roller carried by the extension 26 from the snail-shaped cam surface and permitting the operator to continue an upward motion of the lever 24, thus, engaging the clutch and releasing the brake preparatory to another 30 down stroke of the knife.

The binder 32 operates in grooves 33 in the side members 1, and, below the table 2, is provided with a cross-head 34. The binder is normally held in an elevated position by 35 springs 35 encircling rods 36 suspended by nuts 37. The springs 35, at their lower ends, seat in concave annular grooves in nuts 38, and, at their upper ends, support the binder 32 which has outwardly projecting lugs provided with forks 39 straddling flats on the rods 36 in the manner illustrated in Fig. 2. Projecting through an opening in the cross-head 34 is a piston rod 40 which connects with a piston in the cylinder 41, this cylinder 40 being connected through pipes 42 and 43 with a control valve 44 which communicates with the pump 16 through pipes 45 and 46. It will be apparent from an inspection of Fig. 1 that the cylinder 41 is suitably anchored; and 45 from an inspection of Fig. 2 it will be understood that the cross-head 34 is free to move downwardly when the piston rod 40 is depressed, such rod having a nut 47 which engages with the cross-head 34 when a power 50 effected descent of the binder 32 is desired, and yet permits of manually drawing down the binder without affecting the position of the piston rod or its piston.

For enabling an operator to manually pull 55 down the binder 32, a treadle 48 is provided,

this treadle being preferably counter-weighted as shown in Fig. 1 in order to retain it in an elevated position, and connecting with the cross-head 34 through flexible chains 49. Such chains, when the binder is being operated by the piston rod 40, merely flex or buckle without transmitting the cross-head motion to the treadle 48, this treadle therefore remaining stationary and in the elevated position shown in Fig. 1. The treadle 48 is 70 pivoted to a transverse shaft 50, and this same shaft also carries one end of a second treadle 51 which may be normally held in an elevated position by a compression spring 52. The treadle 51 through a chain 53 connects 75 with a link 54 and is intended for effecting suitable movements of the valve 55, to thereby operate the binder 32 independently of any knife movements, without affecting the position of the handle 24, and without depressing the treadle 48. If desired, the treadle 48 may be employed for drawing down the binder manually and the treadle 51 then operated to admit fluid to the cylinder 41 for obtaining a power effected clamping action. 80 But, as above stated, all binder movements can be produced by the treadle 51 alone, and for securing such treadle in a depressed position a latch 56 is provided, this latch enabling the operator to not only pull down the 85 binder, but to hold it in a power effected clamping position for any desired period of time.

The link 54, as best shown in Fig. 1, has 90 one of its ends connected to the extension 27 and its other end connected to the valve stem 57. The extension 27 has an overlying part 58 which normally contacts with the top surface of the link 54 and yet allows such surface to be moved downwardly by the treadle 51 without thereby moving the handle 24. When movement of the valve stem 57 is effected by the handle 24, the part 58, of course, comes into contact with the link 54 and through 95 such link operates the valve stem 57. The valve stem 57 is normally held in an elevated position by a spring 59, and all valve movements are resisted by such spring which also functions to return the valve stem after having been forced down either by the treadle 48 or by manipulation of the lever 24.

As best shown in Fig. 3, the valve 44 encloses a reciprocable member 55, such member, when in the elevated position produced by the spring 59, placing the inlet pipe 45 in communication with a tube 43 leading to the bottom of the cylinder 41, and the outlet pipe 46 in communication with a tube 42 leading to the top of the cylinder 41, these connections being respectively made 100 through a circumferential groove 60 and radial and longitudinal passageways 61 and 62. As shown in Fig. 3, the valve 55 is in a neutral or inoperative position, such position being maintained by means hereinafter 105

fully described. In this neutral position fluid from the inlet 45 circulates downwardly through the bore 62 and returns to the pump through the pipe 46. When forced further down, the valve 55 places the inlet pipe 45 in communication with the tube 42 through a circumferential groove 63, and the outlet pipe 46 in communication with the tube 43 through the ducts 61 and 62, thereby pulling down the binder.

From the foregoing description it will be evident that the binder may be set either by treadle 48 or treadle 51 depending upon whether or not it is desired to actuate the binder manually or by power. It will also be noted that this may be done before the cutter is set in operation by lever 24. However, when desired the cutter and binder can be made to operate simultaneously by said lever 24, thus dispensing entirely with the operation of treadles 48 and 51. This result is made possible through the coaction of the extension 58 on the lever 24, which extension necessarily depresses the valve stem 57 so that the binder operates simultaneously with the cutter.

As shown in Fig. 2, the bracket 65 which is rigidly secured to the member 34 has extending therefrom an ear 66 adapted to movably secure the rod 67. The rod 67 has a collar 68 slidably mounted thereon which may be fixed thereto in any desired position by means of the set screw 69. The upper end of the rod 67 has rotatably secured thereto the lever member 70 pivoted at 71 in the rigid projection 72. The lever member 70 has an end 73 extending therefrom and adapted to engage the upper end of the valve stem 57. When the binder is operated in its fully open position, the collar 68 is secured to the shaft 67 in such a position that when the binder reaches its fully open position, the ear 66 of the bracket 65 will strike the collar 68 thereby actuating the lever 72 which will move the reciprocal member 55 of the valve to the neutral position, thereby relieving the operating mechanism from the strain to which it would be subjected were the binder permitted to pass upwardly against its stop without a disconnection of the hydraulic operating mechanism. By a different setting of the collar 68 on the rod 67, the ear 66 of the bracket 65 on the member 34 can be made to strike such collar 68 and thereby move the reciprocal member 55 of the valve to the neutral position before the binder has moved to the fully open position. This arrangement permits operation of the binder to a partially open position when bundles of paper less than the full thickness ordinarily taken by the cutter are operated upon. The further advantage of this automatic control, as hereinbefore stated, is to disconnect the hydraulic operating mechanism from the binder when it has reached its fully open

position, thereby relieving the strain to which the hydraulic operating mechanism would otherwise be subjected.

The pump 16 may circulate oil or other suitable fluid for effecting the desired binder movements. The particular pump used has a variable displacement at a constant speed, is provided with valves for relieving excessive pressure, makes provision for varying the pressure at the discharge, and delivers a practically pulsationless current of oil. These characteristics, and especially the last, are desirable in a pump used for binder operation because any irregularity of the binder motion is likely to skew or otherwise disarrange the paper being cut, and different papers do not require the same binder pressures.

From the foregoing description, it will be apparent that our invention, by the provision of a fluid pressure controlled binder for paper cutting machines, not only greatly simplifies their construction, but also makes valuable advances in the way of a more versatile control system. The control gear provided makes possible the following features: independent manual operation of the binder; independent power operation of the binder; synchronized binder and knife movements; static binder pressure exerted for any desired period of time; variable binder pressure; continuous pump action; uniformly applied pressure, increased binder speed; variable binder speed; and, finally, a more efficient and generally satisfactory arrangement for effecting the specified functions.

Other modes of applying the principle of our invention may be employed instead of the one explained, change being made as regards the structure herein disclosed, provided the means stated by any of the following claims or the equivalent of such stated means be employed.

We therefore particularly point out and distinctly claim as our invention:

1. In a paper cutting machine, a mechanically operated knife, a hydraulically operated binder, control means for actuating said binder manually independently of said knife, means operating said binder when said knife is operated, means for stopping the knife at the top of its stroke and adjustable means for stopping the binder in its upward stroke at any desired point.

2. In a paper cutting machine, a mechanically operated knife, a hydraulically operated binder, control means for actuating said binder hydraulically independently of said knife, means operating said binder when said knife is operated, means for stopping the knife at the top of its stroke and adjustable means for stopping the binder in its upward stroke at any desired point.

3. In a paper cutting machine, a mechanically operated knife, a hydraulically op-

erated binder, control means for actuating said binder manually or hydraulically independently of said knife, said manual and hydraulic means being capable of joint operation, means operating said binder when said knife is operated, means for stopping the knife at the top of its stroke and adjustable means for stopping the binder in its upward stroke at any desired point.

⁵ ¹⁰ Signed by us, this 24th day of September, 1929.
